UNITED STATES PATENT OFFICE.

ANTON N. HORNUNG, OF LOS ANGELES, CALIFORNIA.

DESIGN FOR A REFRIGERATOR.

Application filed September 8, 1925. Serial No. 14,723. Term of patent 14 years.

To all whom it may concern:

Be it known that I, ANTON N. HORNUNG, a citizen of the United States, residing at Los Angeles, in the county of Los Angeles and State of California, have invented a new, original, and ornamental Design for a Refrigerator, of which the following is a specification, reference being had to the accompanying drawing, forming a part thereof.

The figure is a perspective view of a refrigerator the front of which shows the dominant feature of my new design.

I claim:

The ornamental design for a refrigerator as shown.

Signed at Los Angeles, in the county of Los Angeles, and State of California, this 1st day of September, 1925.

ANTON N. HORNUNG.
